UNITED STATES PATENT OFFICE.

JAMES H. WOODBURY, OF SOMERVILLE, MASSACHUSETTS.

DESIGN FOR A HANDLE FOR SHOE-TREES.

No. 38,286.

Specification for Design.

Patented Oct. 16, 1906.

Application filed March 17, 1904. Serial No. 198,686. Term of patent 14 years.

To all whom it may concern:

Be it known that I, JAMES H. WOODBURY, a citizen of the United States, residing at Somerville, in the Commonwealth of Massachusetts, have invented a new, original, and ornamental Design for a Handle for Shoe-Trees, of which the following is a specification, reference being had to the accompanying drawings, forming part hereof.

In the drawings, Figure 1 is a side elevation of a shoe-tree handle, showing my new

design. Fig. 2 is a top plan view thereof. Fig. 3 is a view in end elevation looking at the right-hand end of the preceding figures.

I claim—

The ornamental design for a handle for shoe-trees as shown.

JAMES H. WOODBURY.
